UNITED STATES PATENT OFFICE.

DUDLEY T. FISHER, OF COLUMBUS, OHIO, ASSIGNOR TO THE JEFFREY MANUFACTURING COMPANY, A CORPORATION OF OHIO.

LOCOMOTIVE.

1,132,838.

Specification of Letters Patent. Patented Mar. 23, 1915.

Application filed April 16, 1910. Serial No. 555,787.

To all whom it may concern:

Be it known that I, DUDLEY T. FISHER, a citizen of the United States, residing at Columbus, in the county of Franklin and

5 State of Ohio, have invented certain new and useful Improvements in Locomotives, of which the following is a specification, reference being had therein to the accompanying drawing.

10 This invention relates to electric locomotives and particularly to those wherein a portion of the motor, as the armature, is mounted upon or so connected to the driving axles as to dispense altogether with 15 gearing.

The object of this invention is therefore the development of a gearless locomotive and, to that end, the invention consists in the structure of parts and in their combination 20 substantially as hereinafter set forth and claimed.

In the accompanying drawings which form a part of this specification, Figure 1 represents in side elevation a locomotive 25 embodying the present invention; Fig. 2 represents a longitudinal, vertical section through the motor frame of the locomotive showing the armatures and field magnets of the motors in elevation; Fig. 3 is a vertical, transverse section through the locomotive taken in the plane indicated by the line 3—3 Fig. 1; and Fig. 4 is a vertical, transverse section of the apparatus seen in Fig. 3 taken in the plane indicated by the 35 line 4—4.

In this locomotive as at present designed, two motors are associated and they are mounted in the locomotive frame designated by 5. The driving wheels are designated 40 by 6 and their axles by 7. The axles are preferably journaled in axle boxes spring mounted in the sides of the locomotive frame. In mounting and connecting up the driving motors, a motor frame is constructed of a width to extend practically from one 45 wheel 6 to the other and is fixed in vertical position in the locomotive frame by any suitable means as by angle bars indicated at 8 which extend from one side to the other of the frame 5. The motor frame consists 50 preferably of a base piece as 9 provided with a middle column 10, and two angle plates 11 and 12 connected at their lower ends to the base piece and at their upper ends to the 55 column 10. In cross-section this frame ap-

pears as in Fig. 3 and has side pieces as 13 which close up the frame and with it form a housing for the field magnets and armatures.

The column 10 divides the motor frame 60 into two compartments and through each compartment passes one of the driving axles. Extending about each axle from driving wheel to driving wheel is located a sleeve 14 which is sufficiently larger than 65 the axle to allow for the play of the latter due to the spring mounting thereof in the locomotive frame. To each of these sleeves is fixed an armature 15 with its commutator designated at 16. To provide for as 70 large an armature as possible, proportionate to the height of the locomotive, only the horizontal and upper field poles, 17 and 18 respectively, are provided with coils, the lower ones 19 being left as consequent poles. 75 Each sleeve 14 is journaled in the side plates 13 of the motor frame and preferably by ball bearings as indicated. These bearings are close to the ends of the armature and close to the said bearings at the outside of 80 the motor frame there are fixed upon the sleeve disks as 20 from which driving connection is made to the driving wheels.

The driving wheels, as indicated (Fig. 3), are cupped on their inner sides to provide for housing the driving disks and the driving connections. These driving connections must be of a yielding construction to provide for the relative vertical movement between the disks and the driving 90 wheels. Such connection is also preferably of a sort such that it will yield somewhat to the torque of the motor in starting and the momentum of the locomotive in stopping. A connection for this purpose is typified in 95 Figs. 3 and 4. Opposed levers as 21, in pairs, are pivoted to the wheel 6. Between their outer ends coiled springs as 22 are located, while between their inner ends pins as 23 project from the disks 20. Stop pins 100 as 24 may be provided for the outer ends of the lever 21.

The structure of the armature, their commutators and brushes have not been shown nor has the circuiting been indicated, since 105 they are well known and form no specific part of this invention.

Locomotives embodying my invention are especially intended for under-ground use in mines or in freight tunnels. In locomotives 110

2

of this class great power is required but at the same time the external dimensions of the locomotive must be kept within certain relatively small limits. By providing a consequent pole below the armature I am enabled 5 to provide a much larger armature than would be the case if all four of the poles were provided with coils. It is also very desirable, and in fact essential, when a locomotive is being used for mines that the electrical parts of the motor be inclosed, not only to exclude dust and dirt, but also to exclude explosive gases which are frequently met with and which might be fired by sparks 10 from the commutator. In the construction which I have shown and described there is provided a very powerful and at the same time compact motor arrangement which is inclosed in a tight casing.

15 20 The invention claimed is:—

1. In an electric locomotive, the combination of a main frame, two transverse axles on which the frame is supported, track wheels at the ends of the axles, a continuous box-like motor field frame having a central partition which divides it into two similar compartments, means for mounting the field frame on the main locomotive frame with the axles passing through the said compartments considerably below the centers thereof, the frame extending at the top beyond 25 the peripheries of the wheels and terminating at the bottom inside the peripheries of the wheels, motor armatures mounted in the

compartments normally concentrically with 35 the axles and connected thereto, and four motor poles in each compartment for co-operation with the armature, one pole being located above the armature and provided with a coil, two poles being located at the 40 sides of the armature and provided with coils, and the fourth pole being located below the armature and not provided with a coil.

2. In an electric locomotive, the combination 45 with the frame of the locomotive, of driving wheels having their axles journaled in said frame, a vertically disposed motor frame secured to the locomotive frame and having a base piece provided with a middle column and having also two angle plates 50 one secured to each end of said base piece and to the top of said column thereby forming two compartments through which said axles pass, a wound field pole upon each 55 side of said column in each compartment and another upon the uprights of each angle plate, an armature mounted upon each axle transversely of each compartment, and driving connections between the armature and 60 the driving wheels.

In testimony whereof I affix my signature, in presence of two witnesses.

DUDLEY T. FISHER.
